BASE FOR OUTDOOR LIGHTING FIXTURE

William F. Harris, Jr., 6256 Deveron Drive,
Charlotte, N.C. 28211

Filed Feb. 22, 1971, Ser. No. 117,874

Term of patent 7 years

Int. Cl. D26—03

U.S. Cl. D48—31

Fig. 4

Fig. 5

Fig. 6

Fig. 7

FIG. 1 is an elevational view of a base for an outdoor lighting fixture embodying my new design;

FIG. 2 is a side elevational view thereof taken from the right of FIG. 1.

FIG. 3 is a top plan view thereof;

FIG. 4 is an elevational view thereof with the upper portion of the base being tilted;

FIGS. 5, 6 and 7 are elevational views of the base in the tilted position successively rotated to the left.

I claim:

The ornamental design for a base for outdoor lighting fixture, as shown.
